(57) **CLAIM**

The ornamental design for a cleaning wipe, as shown and described.

DESCRIPTION

FIG. 1 is a perspective view of a cleaning wipe showing the new design;

FIG. 2 is a top view of the cleaning wipe of FIG. 1;

FIG. 3 is a bottom view of the cleaning wipe of FIG. 1;

FIG. 4 is a side view in the direction of line 4-4 in FIG. 2;

FIG. 5 is a side view in the direction of line 5-5 in FIG. 2; and,

FIG. 6 is a side view in the direction of line 6-6 in FIG. 2.

The shading and broken line portions of the disclosure are for illustrative purposes only and form no part of the claimed design.
